UNITED STATES PATENT OFFICE.

ROBERT A. FORBES, OF HAMILTON, OHIO, ASSIGNOR OF ONE-FIFTH TO ARTHUR F. MILLER, OF HAMILTON, OHIO.

ENGINE.

Application filed September 21, 1925. Serial No. 57,657.

This invention relates to internal combustion engines, and particularly to means for facilitating the starting of such engines.

One of the principal objects of the invention is to provide means for reducing the load or resistance to engine cranking resulting from the compression and expansion of gases within the engine cylinder due to the movement of the engine piston. Another object is to provide an engine with auxiliary means for operating certain valves from the valve gear of other valves.

Still another object of the invention is to so reduce resistance to engine cranking as to enable the engine to be cranked by a small dynamo electric machine having a permanent driving connection with the engine and adapted to operate as a generator after the engine has become self-operative.

20 A further object is to provide as an attachment or an accessory for a self-contained engine, means for reducing the resistance to engine cranking resulting from compression and expansion of the gas in the engine cylinder.

25 The present invention is shown, for convenience in illustration, as associated with a four cylinder, four-stroke-cycle internal combustion engine of a well known make, but it will be understood that the invention may be readily applied to other forms of engines.

Referring to the drawing Fig. 1 is a fragmentary plan view somewhat diagrammatic in form, of a motor vehicle having the present invention embodied therein;

35 Fig. 2 is a fragmentary side elevation of the engine illustrated in Fig. 1 showing the present invention associated therewith:

Figs. 3, 4, and 5, are enlarged vertical sectional views taken on the lines 3—3, 4—4, and 5—5 of Fig. 2;

Fig. 6 is a section on the line 6—6 of Fig. 5;

Fig. 7 is a fragmentary sectional view on the line 7—7 of Fig. 2, parts being omitted for clearness in illustration;

Fig. 8 is an enlarged detail taken on the line 8—8 of Fig. 1, and

Fig. 9 is a section taken on the line 9—9 of Fig. 2.

50 Referring particularly to Fig. 1 of the drawing, 20 represents the chassis of a motor vehicle having mounted thereon an internal combustion engine 21 herein illustrated as a four cylinder water-cooled engine of the four-

stroke-cycle type. As is well understood in 55 the art, such an engine comprising generally a cylinder block having cylinders bored therein, pistons reciprocable in the cylinders, and a crankshaft connected with the pistons by means of connecting rods, all of usual construction and therefore not illustrated herein.

The engine 21 is provided at the front end of the crankshaft with the usual hand crank 22 for cranking the engine. The engine is also provided with a starting, lighting and 65 ignition system, and engine cranking may be accomplished electrically by pressing a starting switch button 25, which is accessible from the driver's seat, and which when depressed closes a circuit from the battery 26 through 70 the dynamo electric machine 27 to operate the latter as a motor. The dynamo electric machine is connected with the engine crankshaft through a suitable chain drive 28, gears, or other driving connection, the ratio of speed 75 between the armature of the dynamo electric machine 27 and the crank shaft of engine 21 being preferably the same whether the dynamo electric machine 27 is operable as a motor or as a generator. The electrical sys- 80 tem may be provided with a voltage coil 29 having an armature 30 which is attracted when the dynamo voltage rises to a predetermined value, thereby connecting the battery 26 with the dynamo electric machine 27, to be 85 charged thereby.

Internal combustion engines of the most approved form generally offer considerable resistance to cranking, a large part of which is attributable to the load which results from 90 the compression and the expansion of the gases in the cylinder by reason of the movements of the piston, and particularly to the irregularity of such load. The resistance to engine cranking resulting from this and other 95 causes, particularly when the engine is new or is exposed to low temperatures, is often so great that many users of motor vehicles are compelled to go to the expense of purchasing electrical starting equipment, but even when such equipment is employed, the high resistance to engine starting results in 100 excessive demand upon the battery and consequently early depletion thereof.

The present invention contemplates the 105 provision of an attachment or accessory for the elimination or reduction of resistance to engine cranking resulting from expansion

and compression of gases in the engine cylinder, thereby greatly facilitating the engine cranking operation.

Referring particularly to Figs. 2 to 7, 35, 36, 37, and 38 represent the exhaust valve stems of the four cylinder engine illustrated in Fig. 1, while 40, 41, 42, and 43 represent the stems of the intake valves. The valves are normally held to their seats by suitable valve springs, springs 45 being provided for the exhaust valves and springs 46 for the intake valves. The engine is provided with the usual means for raising or unseating the valves, such means comprising push rods 47 the upper ends of which are adapted to abut the lower ends of the valve stems, and the lower ends of which ride upon and are adapted to be actuated by valve cams carried by the camshaft, the construction and arrangement of such cams and camshafts being well known to those skilled in the art and therefore not deemed necessary to be illustrated. The usual arrangement in a four cylinder engine, such as illustrated, is such that two of the pistons are on their up strokes at the same time, while the other two pistons are on their down strokes. In Fig. 2 the pistons for cylinders Nos. 1 and 4 are assumed to be moving upwardly together while the pistons in cylinders Nos. 2 and 3 are moving downwardly together. If the piston in cylinder No. 1 is on its exhaust stroke then the piston in cylinder No. 4 is on its compression stroke, and likewise if the piston in cylinder No. 2 is on its intake stroke then the piston in cylinder No. 3 is on its firing stroke. The arrangement of cams on the camshaft is of course such as to operate the intake and the exhaust valves in their proper sequence to cause continuous normal operation of the engine, and the mechanism for operating each of the valves, from the valve stem connected with the valve to the cam mounted upon the camshaft, is hereinafter referred to as the valve gear.

Referring to Figs. 3 and 4 showing details of the exhaust valve operating mechanism, it will be seen that the exhaust valve springs 45 bear at their upper ends against the cylinder block and at their lower ends upon a washer-like valve-spring seat 50 retained upon the valve stem by a pin 51. Loosely mounted upon the exhaust valve stems are rings or collars 55, 56, 57, and 58 which are joined together in pairs, collars 55 and 56 being joined by rod 59, and collars 57 and 58 being joined by rods 60. These collars surrounding the exhaust valve stems are interposed between the pins 51 and the push rods 47, and being smaller than the push rods 47, they are raised by the latter simultaneously with the valve stems with which they are associated.

A frame or bracket 63 is fixedly mounted in front of the several valve gears at a level

adjacent the lower ends of the valve stems, being detachably secured to the cylinder block by means of studs 64, as best illustrated in Fig. 9. The stud 64 engages in screw threaded opening 65 in the cylinder block, 70 which opening normally receives the screw threaded bolt by which a cover is secured over the valve mechanism. The screw threaded bolt, above referred to, is removed and replaced by the stud 64, the bracket 63 being 75 rigidly held in place upon the stud 64 by means of suitable fastening devices 66. The outer end of the stud 64 is extended sufficiently to receive a cover (not shown) for enclosing the valve mechanism. 80

Bracket 63 is provided adjacent its ends with upwardly extending lugs 68 which are provided with inwardly opening slots 69 adapted to serve as bearings for a rocker shaft 70 which extends lengthwise of the 85 bracket 63 and lies between said bracket and the push rods 47, as best shown in Fig. 4. The rocker shaft 70 carries transversely extending arms 71 having elongated slots 72 which are adapted to engage the rods 59 and 60 adjacent the exhaust valve stems 35 and 38 respectively. A short rocker shaft 75 is mounted upon the central portion of the long rocker shaft 70, as shown in Figs. 3 and 7, and the short rocker shaft is provided with 90 slotted arms 76 similar in construction and arrangement to the slotted arms 71 upon the long rocker shaft, the slotted arms 76 engaging the rods 59 and 60 adjacent to the exhaust valve stems 36 and 37 respectively. 95

The position of the rocker shafts 70 and 75 during normal operation of the engine is shown in full lines in Figs. 3, 4, and 7, and it will be noted that the slots which engage the rods 59 and 60 are substantially vertical so 105 that rising and falling movements of the rods 59 and 60 caused by corresponding movements of the exhaust valves, have no affect upon the rocker shafts 70 and 75 since the rods 59 and 60 simply slide up and down 110 in the slots formed in the arms 71 and 76.

To relieve compression during engine starting, rocker shaft 70 is moved into the bearing slot 69, as shown in dotted lines at 70^a in Fig. 4, such movement of course carrying with it the rocker shaft 75. Rocker shaft arms 71 and 76 are now substantially horizontal and it will be apparent that any rising or falling movement of the exhaust valve adjacent one of the arms 71 will be transmitted through the long rocker shaft 70 and other arm 71 to the exhaust valve associated therewith. It has been assumed herein that the piston in cylinder No. 1 is moving upwardly on its exhaust stroke, and consequently the valve stem 35 is elevated during this stroke to hold the exhaust valve open. Such elevation of the exhaust valve stem 35 of cylinder No. 1 is transmitted through the 120 rocker shaft 70 to the exhaust valve stem 38 125 130

of cylinder No. 4, the piston of which has been assumed to be moving upwardly on its compression stroke. The exhaust valve stem 38 of cylinder No. 4 is thus operated by the 5 exhaust valve gear of cylinder No. 1, thereby relieving the compression in cylinder No. 4. Similarly when exhaust valve stem 38 is elevated during the exhaust stroke of cylinder No. 4, such movement will be transmitted 10 through rocker shaft 70 to exhaust valve stem 35 to relieve compression in cylinder No. 1.

At the time of upward movement of the pistons in cylinders Nos. 1 and 4, the pistons in cylinders Nos. 2 and 3 are moving downwardly and the exhaust valves are inactive, 15 and as a consequence no movement is transmitted through the short rocker shaft 75. But when either of the pistons in cylinders Nos. 2 and 3 move upwardly on their exhaust 20 strokes there is a lifting movement of the corresponding exhaust valve stem and such movement is transmitted by means of the short rocker shaft 75 and the rocker arms 76 to the other exhaust valve thereby relieving 25 compression in the other cylinder.

Means is also provided for relieving the resistance to engine cranking resulting from the partial vacuum caused by expansion or rarefaction of the gas in the cylinders during 30 the down strokes of the pistons. Such means is preferably so associated with the rocker shaft 70 and arranged as to be rendered operative or inoperative by movement of the rocker shaft between its full line and dotted 35 line positions, shown in Fig. 4. Referring more particularly to Figs. 5 and 6 showing details of construction and the valve gear of an intake valve, intake valve spring 46 is compressed between a wall of the cylinder 40 block and valve spring seat 80 which is slidably mounted upon a shouldered sleeve 81, the sleeve 81 being in turn guided upon valve stem 43 and held against downward movement thereon by a pin 82. An auxiliary valve 45 spring 83 is mounted upon the valve stem 43 and is compressed between a boss on the cylinder block and washer 84 guided on valve stem 43 and bearing upon the sleeve 81.

Extending from the bracket 63 adjacent 50 each of the intake valves is a pair of arms 85, upon which are pivoted at 86 forked arms 87 engaging the long rocker shaft 70. The forked arm 87 is adapted to be swung by the rocker shaft 70 between its inoperative 55 position shown in full lines in Fig. 5, and its operative position shown in dotted lines in this figure. Each forked arm 87 carries upon its pivot shaft 86 a cam 88 which is adapted to engage the spring seat 80 for the purpose 60 of raising the same from the flanged sleeve 81, or for lowering the same into engagement with flanged sleeve 81. The arrangement of the parts is such that when the rocker shaft 70 is in its lower or inoperative position, as 65 shown in full lines in Fig. 5, the spring seat

80 bears upon the flanged sleeve 81, so that both the main spring 46 and the auxiliary spring 83 are active in holding the intake valve to its seat. But when the rocker shaft 70 is moved to its operative position for engine cranking, as indicated in dotted lines in Fig. 5, the cams 88 serve to hold the spring seat 80 in elevated position, out of engagement with the flange of sleeve 81, so that now only the auxiliary and weaker spring 75 83 exerts pressure to hold the intake valve to its seat. It is apparent, therefore, that a lesser suction or expansion of the gas within the cylinder on the down stroke of the piston will suffice to open the intake valve. The 80 springs are so proportioned that a normal spring pressure is exerted upon the intake valve during engine operation, but during engine cranking the spring pressure is greatly reduced so as to permit the intake valve to 85 open to admit gas and thus break the partial vacuum in the cylinder. The valve seat 80 may be lifted to any desired height during engine cranking, but it is found in practice that excellent results are attained with a lift 90 of one-sixteenth inch, this allowing sufficient opening of the intake valve to break the partial vacuum within the cylinder at cranking speeds.

Mechanism for moving the rocker shafts 95 between their operative and inoperative positions comprises a pair of spaced brackets or arms 100 carried by the bracket or frame 63, between which arms there is pivoted at 101 a rock lever 102 which is forked at its 100 lower end to receive the rocker shafts 70 and 75 as shown in Fig. 3. The upper end of rocker lever 102 is connected by means of a rod 103 or other suitable connection with the arm 104 on control shaft 105, which control 105 shaft preferably extends longitudinally of the motor vehicle and is mounted for rocking movement thereon. A spring 106 is connected between the rod 103 and a fixed part of the engine or of the motor vehicle for normally holding the auxiliary valve-control mechanism in inoperative position. As shown in Fig. 1 the fixed end of the spring 106 is connected to a projection or fin extending from the wall of the opening 107 formed in 110 the cylinder block, in which opening the rod 103 is located.

The auxiliary valve control mechanism is preferably controlled from a plurality of positions, for which positions the operator may 120 be either on the motor vehicle or on the ground. Referring to Fig. 1 the control shaft 105 is provided with a handle 108 at its front end adjacent the hand crank 22, whereby the valve control mechanism may be readily rendered operative to reduce resistance to engine cranking when the cranking is done by hand at 22. Preferably means is also associated with the starter button 25 of the electrical starter whereby resistance to en- 125 130

gine cranking may be reduced when cranking electrically. One form of such means is illustrated in Figs. 1 and 8 in which there is shown an arm 111 rigidly mounted on the 5 control shaft 105, the outer end of such arm lying in the path of movement of the pedal 112. The pedal 112 is normally held in raised inoperative position by a spring 113, and has an enlarged head which overlies the starter 10 button 25. To crank the engine the operator may press the pedal 112 down with his foot, thereby first rotating the control shaft 105 to bring the auxiliary valve operative mechanism into operating position. Continued 15 movement of the pedal 112 causes the same to engage and depress the starter button 25 thereby placing in operation the electrical cranking means. As soon as the engine becomes self-operative, the driver of the vehicle 20 removes the foot pressure upon the pedal 112, thereby restoring the electrical starter and the auxiliary valve control mechanism to their inoperative positions.

From the foregoing it will be apparent that 25 the present invention provides a simple and inexpensive means for reducing the resistance to engine cranking which results from the compressive and expansive movements of the pistons in their cylinders. During the up 30 strokes of the piston, the exhaust valves are held open to relieve compression, and during the down strokes of the pistons, the intake valves are either opened or held to their seats under such reduced pressure as to offer but 35 slight resistance to engine cranking as a result of expansion of the gases in the cylinders. The operation of the intake valves is such that a proper explosive fuel mixture is taken into each cylinder on its intake stroke and such 40 explosive mixture is still in the cylinder at the time of ignition during the firing stroke, although it will be observed that the fuel mixture is not under the usual compression owing 45 to the fact that the compression valve was held open during the compression stroke. However, it has been found that the uncom- 50 pressed fuel mixture burns or explodes readily and a single explosion of such uncom- pressed fuel mixture liberates sufficient power 55 to put the engine in motion. Consequently the cranking may be discontinued after a few explosions of the engine and, the auxiliary mechanism being thrown into its inoperative position, the engine will continue to operate in its normal manner.

An important advantage of the present invention is that the resistance to engine cranking 60 may be reduced to such an extent as to render hand cranking unobjectionable in most instances. In fact the hand cranking means may be mounted in such a position that it may be operated from the driver's seat, thereby overcoming one of the great objections to hand cranking as now practiced, namely, the 65 necessity for getting out of the motor vehicle

to operate the hand crank. Even when an electrical starter is used to crank the engine, the present invention constitutes a valuable adjunct in that it effects a great saving in current during engine cranking and avoids early 70 depletion of the battery. The advantage in the saving of current is so marked that in some cases the present invention enables the use of a smaller battery and hence effects a saving 75 in the cost of the electrical equipment. 75

As a result of the greatly reduced resistance to engine cranking, it is feasible to so construct a dynamo electric machine 27 that it may be operable both as a cranking motor and as a generator without the introduction of 80 the variable driving gears which are at present required in single unit starters owing to the fact that the power of the motor must be greatly multiplied in order to overcome the high cranking resistance. In single unit 85 starters of the known types the gearing which is suitable for cranking the engine, is not suitable for driving the dynamo electric machine as a generator after the engine becomes self-operative, owing to the fact that the dynamo 90 electric machine would be operated at too high a speed. Therefore, such single unit starters commonly have means for changing the gear connection between the engine crank-shaft and the armature shaft of the dynamo- 95 electric machine when the latter changes from a motor to a generator. As already suggested, the present invention permits the elimination of such gear changing mechanism which at best is complicated and expensive 100 and which greatly complicates the electrical construction of the dynamo-electric machine. Obviously the present invention enables the practice of important economies in the cost of the electrical starting and generating system, and also enables the simplification thereof. 105

From the construction as disclosed in the drawing, it is apparent that the present invention may be readily applied as an accessory to 110 self-contained engines.

While the form of apparatus herein described constitutes a preferred embodiment of the invention, it is to be understood that the invention is not limited to this precise 115 form of apparatus, and that changes may be made therein without departing from the scope of the invention which is defined in the appended claims.

What is claimed is:

1. In a multiple cylinder engine comprising intake and exhaust valves for each of the cylinders, valve gear for operating each of said valves, said valves being operated in a predetermined sequence to produce continuous operation of the engine, and auxiliary means for operating one of said valves from the valve gear of another valve during engine starting. 125
2. In a multiple cylinder engine comprising 130

ing intake and exhaust valves for the cylinders, valve gear for operating each of said valves, said valves being operated in a predetermined sequence to produce continuous operation of the engine, and auxiliary means for operating one of said exhaust valves from the valve gear of another exhaust valve.

3. In a multiple cylinder engine comprising intake and exhaust valves for the cylinders, valve gear for operating each of said valves, said valves being operated in a predetermined sequence to produce continuous operation of the engine and auxiliary means for operating one of said exhaust valves from the valve gear of another exhaust valve, and means for rendering said auxiliary means operative or inoperative.

4. In a multiple cylinder engine comprising intake and exhaust valves for each of the cylinders, valve gear for operating each of said valves, said valves being operated in a predetermined sequence to produce continuous operation of the engine, and auxiliary means adapted to be connected with the valve gear of the exhaust valves of two of said cylinders whereby valve-opening movement of either of said valve-gears causes simultaneous opening of the exhaust valve of said other cylinder.

30 5. An internal combustion engine comprising a plurality of valves, valve gear for operating each of said valves, said valves being operated in a predetermined sequence to cause continuous operation of the engine, and auxiliary means for operating one of said valves out of its normal order from the valve gear of another valve.

6. A four-stroke-cycle engine, comprising intake and exhaust valves, yielding-pressure means for normally holding said intake valve closed during normal operation of the engine, and means for reducing without overcoming said pressure means during engine starting, so that the valve may be seated during engine starting.

7. A four-stroke-cycle engine, comprising intake and exhaust valves, yielding-pressure means for holding said intake valve to its seat during normal operation of the engine, a second yielding-pressure means for holding said valve to its seat and means for rendering one of said yielding-pressure means inoperative.

8. A four-stroke-cycle engine comprising a cylinder having intake and exhaust valves, yielding-pressure means normally operable to hold said intake valve to its seat during engine operation, auxiliary yielding-pressure means also adapted to hold said intake valve to its seat, said auxiliary yielding-pressure means exerting a lower pressure on the intake valve than the first-mentioned pressure means, and means for rendering said first-mentioned yielding-pressure means inoperative during engine starting whereby to reduce

the pressure on said intake valve during engine starting.

9. An internal combustion engine of the four-stroke-cycle type comprising a cylinder, intake and exhaust valves for said cylinder, means for cranking said engine, and means for reducing the resistance to engine cranking, said last mentioned means comprising means for reducing the pressure in the engine cylinder during the compression stroke, means for reducing the pressure conditions in the engine cylinder during the firing stroke, and a common control for said two last-named means.

10. An internal combustion engine of the four-stroke-cycle type comprising a cylinder, intake and exhaust valves for said cylinder, yielding-pressure means for holding said valves to their seats, a piston operable in said cylinder, said piston moving upwardly in the cylinder during the compression and the exhaust strokes, and moving downwardly in the cylinder during the suction and the explosion strokes, means for cranking the engine, and means operable during engine cranking for opening the exhaust valve during the up strokes of the piston and for reducing the yielding pressure upon the intake valve during the down strokes of the piston, whereby to reduce resistance to cranking during the engine-cranking operation.

11. An internal combustion engine of the four-stroke-cycle type comprising a cylinder, intake and exhaust valves for said cylinder, yielding-pressure means for holding said valves to their seats, a piston operable in said cylinder, said piston moving upwardly in the cylinder during the compression and the exhaust strokes, and moving downwardly in the cylinder during the suction and the explosion strokes, means for cranking the engine, and means automatically operable upon initiation of the engine-cranking operation, for opening the exhaust valve during the up strokes of the piston and for reducing the yielding pressure upon the intake valve during the down strokes of the piston, whereby to reduce resistance to cranking during the engine-cranking operation.

12. An internal combustion engine of the four-stroke-cycle type comprising a cylinder, intake and exhaust valves for said cylinder, yielding-pressure means for holding said valves to their seats, a piston operable in said cylinder, said piston moving upwardly in the cylinder during the compression and the exhaust strokes, and moving downwardly in the cylinder during the suction and the explosion strokes, means for cranking the engine, and means automatically operable upon initiation of the engine-cranking operation, for holding the exhaust valve open during the up strokes of the piston and for reducing the yielding pressure upon the intake valve during the down strokes of the piston, whereby

to reduce resistance to cranking during the engine-cranking operation, said last-mentioned means being rendered automatically inoperative upon discontinuance of the engine cranking.

13. An internal combustion engine of the four-stroke-cycle type comprising a cylinder, intake and exhaust valves for said cylinder, yielding-pressure means for holding said valves to their seats, a piston operable in said cylinder, said piston moving upwardly in the cylinder during the compression and the exhaust strokes, and moving downwardly in the cylinder during the suction and the explosion strokes, means for cranking the engine, and a single member operable from a plurality of positions during engine cranking for opening the exhaust valve during the up strokes of the piston and for reducing the yielding pressure upon the intake valve during the down strokes of the piston, whereby to reduce resistance to cranking during the engine-cranking operation.

14. In a motor vehicle, an internal combustion engine of the four-stroke-cycle type mounted on said motor vehicle, comprising a cylinder, intake and exhaust valves for said cylinder, yielding-pressure means for holding said valves to their seats, a piston operable in said cylinder, said piston moving upwardly in the cylinder during the compression and the exhaust strokes, and moving downwardly in the cylinder during the suction and the explosion strokes, means operable from the driver's seat of the motor vehicle for cranking the engine, a second means for cranking the engine, means operable during engine cranking for holding the exhaust valve open during the up strokes of the piston and for reducing the yielding pressure upon the intake valve during the down strokes of the piston, whereby to reduce resistance during the engine-cranking operation, and

provisions for associating said last-mentioned means with one of said engine starting means 45 whereby to automatically cause operation of said last-mentioned means during operation of said starting means.

15. An attachment for a self-contained engine of the four-stroke-cycle type having a cylinder, intake and exhaust valves for said cylinder, a crank-shaft, valve gear operable from said crank-shaft for controlling said valves, and means for cranking the engine, said attachment comprising means operable 50 during engine cranking for opening the exhaust valve during the engine compression stroke, means for reducing the normal pressure of the intake valve upon its seat during the explosion stroke, whereby to reduce the 55 resistance to engine cranking, and means for detachably fastening said attachment to a side of the engine.

16. In a four-stroke-cycle internal combustion engine having valves operating as normal inlet and exhaust valves during normal engine operation, means operative during engine starting for causing the exhaust valve to open and close during the exhaust and the normal compression strokes, and means for 60 automatically causing the intake valve to open and to close during the normal power stroke if the engine does not fire while still causing the normal opening and closing of the intake valve during the suction stroke. 75

17. In a four-stroke-cycle internal combustion engine having inlet and exhaust valves therefor, means for automatically causing the intake valve to open and to close during the normal power stroke if the engine does not 80 fire, said means having further provisions for causing the normal opening and closing of the intake valve during the suction stroke.

In testimony whereof I hereto affix my signature.

ROBERT A. FORBES.
